UNITED STATES PATENT OFFICE.

DON M. LEMON, OF BOSTON, MASSACHUSETTS, ASSIGNOR OF ONE-HALF TO ERNEST V. PAGE, OF BOSTON, MASSACHUSETTS.

ERASER FOR TYPE-WRITING MACHINES.

979,316.

Specification of Letters Patent. Patented Dec. 20, 1910.

Application filed January 29, 1910. Serial No. 540,874.

To all whom it may concern:

Be it known that I, DON M. LEMON, a citizen of the United States, resident of Boston, in the county of Suffolk and State of Massachusetts, have made a certain new and useful Invention in Erasers for Use with Type-Writing Machines, and declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a central longitudinal section of my invention, with the parts thereof in parallel relation; Fig. 2 is a perspective view of the same with the parts thereof in the positions assumed when applied to the typewriter, which is partly shown in dotted lines; Fig. 3 is a section on the line 3—3, Fig. 1; Fig. 4 is a detail side view of the ratchet wheel for the rotary shaft; Fig. 5 is a side view, partly broken away, showing a modification; Fig. 6 is a detail side view partly broken away of the joint of the upright carrier; Fig. 7 is a central vertical section of the push rod mechanism; and Fig. 8 is a detail perspective view of the rotary brush.

The invention has relation to erasers for use with typewriting machines to erase the printed impression when desired, and it consists in the novel construction and combinations of parts as hereinafter set forth.

In the accompanying drawings, illustrating the invention, Fig. 1 designates an upright carrier, having at its upper end an incasement 2 having disposed therein a horizontal shaft 3 carrying a fast wheel 4 provided with a circular series of ratchet teeth 4^a, set back therein or inset from its side face 4^b, and a loose hollow grooved wheel 5, mounted upon a sleeve 6^a, forming a part of the incasement and in which the shaft 3, has loose bearings, said wheel 5, containing a helical spring 6 fastened at one end thereof to the sleeve 6^a and at its other end to the wheel, the side wall of the wheel 5 carrying a pivoted pawl 7, in engagement with the teeth of the ratchet. The end portion 3^a of the shaft 3, projecting from the incasement, has surrounding the same a flexible covering 55 or sheath 8 for a flexible shaft 9, said shaft

forming a continuation of the shaft 3 and turning therewith, said flexible shaft having a socket end portion 10 wherein is detachably secured by means of a set screw 11, one end portion of a short shaft 12 carrying the round eraser wheel 13, and having a swivel attachment end 14.

The wheel 5 carries in the groove thereof a flexible strap or cable 15, wound thereupon, fastened at one end thereto and having a loose handle end 16, whereby when the strap is pulled out, which should be done with a quick movement, the wheel is rotated, the ratchet wheel 4 and shafts 3 and 9 turning therewith to rapidly rotate the eraser wheel, which through the medium of the flexible shaft held at its end by the swivel attachment, is readily applied to the point to be erased. When the strap 15 is released it is automatically wound again upon the wheel 5 by means of the helical spring, the wheel 4, the flexible shaft and the eraser being unaffected by the opposite rotation of the pawl during this return movement.

The wheel 4 is designed to be of such size 80 and weight as to act somewhat as a fly-wheel to give greater momentum.

The device is conveniently attached to the typewriting machine by means of a screw clamp 17 for attachment to the right hand 85 front post of the frame, and having a pivot stud 18 carrying a swinging arm 19 upon the free end portion of which the upright carrier 1 has support, moving therewith in an arc of a circle of which the pivot stud is 90 a center, so that the whole device may be brought forward for use and folded back again out of the way, or it may be swung around forwardly to rest over the keys of the typewriter.

In the modified form of the invention, as shown in Fig. 5 of the drawings, a rigid shaft 20 is substituted for the flexible shaft, this shaft 20 carrying at its end the eraser wheel, which is turned in the same manner as before stated for the main form of the invention. In this case however the upright carrier is formed in two parts 21, 21^a, having a pivotal joint at 22 whereby the rigid shaft 20 carrying the eraser may be 100 swung upward to bring the eraser in contact with the printed matter, and allowed to drop down again out of the way. A set screw 23 serves to hold the parts of the upright carrier at any angle desired.

In some cases I may use push rod mechanism for pressing the eraser against the type impression to be erased, as shown in Fig. 7 of the drawings. This mechanism comprises a supporting bar 24, designed in application to overlie the top of the typewriter machine frame at one side, and having adjustable grip pieces or screw clamp blocks 25, 25, which will embrace said frame top. The bar 24 has a right-angle head 26, chambered or bored to receive the reciprocatory push rod 27, a retracting spring 28 surrounding the push rod and having a bearing against a collar 28^a thereof and against the end wall 28^b of the bore, serving to return the push rod to normal position after operation. The push rod carries at its inner end a vertical ring or snap-hook 29, having a sliding arcuate part 30 working against a pressure spring 31, which holds said part 30 normally in projected position to close the ring.

In use the end of the flexible shaft carrying the eraser is placed within the ring or snap hook 29, which is first opened by pressing back the sliding piece 30, an indentation of the covering or sheath for the flexible shaft engaging the wall of the snap-hook and serving to hold the eraser in the position desired. The push rod is now operated to press the eraser against the matter to be erased, and the flexible strap or cable operated to rotate the eraser until the matter is erased, when the push rod is released and the parts returned automatically to normal position, the eraser being carried therewith to normal position out of contact with the typewriter platen.

The eraser and flexible shaft carrying the same may be removed from the snap hook at any time, as will be obvious.

The eraser is designed to strike the platen a little to one side of the point where the type strike the platen, to avoid interference with the typewriter ribbon.

The invention is shown as provided with means of attachment to the visible Remington typewriter, but other means of attachment for other typewriting machines may be provided without departure from the spirit of the invention.

The free adjustment of the parts of the carrying frame in connection with the flexibility of the shaft upon which the eraser is borne, will allow the eraser to be applied to matter for erasure either while the paper bearing such matter is upon the typewriting machine or apart from the same upon the adjacent table.

In the application of the invention to typewriting machines the carriage of which lifts upward, the push rod mechanism described may not be used, the eraser being applied by hand pressure, as first described.

A rotary brush attachment 33 may be sub-

stituted for the eraser wheel, for cleaning the type of the machine when desired.

Having thus described my invention, what I claim as new and desire to secure by Letters Patent is:

70

1. An erasing attachment for typewriting machines, comprising a clamp for connection with the typewriter frame, an upright vertically adjustable arm carried by said clamp and having a casing at its upper end, a rotary shaft having journal bearings in said casing and an extension carrying an eraser wheel, and means for rotating said shaft and eraser wheel including a hollow grooved wheel in said casing upon said shaft, a flexible strap having attachment at one end thereof to and wound upon said grooved wheel, and spring means within said hollow grooved wheel for rewinding the strap after operation thereof.

80

2. An erasing attachment for typewriting machines, comprising a clamp adapted for connection with the typewriter frame, a horizontal swinging arm having a pivotal connection with said clamp, an upright arm having connection with said horizontal arm and having a casing at its upper end, a rotary shaft having journal bearings in said casing and an extension carrying an eraser wheel, and means in said casing for rotating said shaft and eraser wheel.

90

3. An erasing attachment for typewriting machines, comprising a clamp for connection with the typewriter frame, an upright arm carried by said clamp and having a casing at its upper end, a rotary shaft having journal bearings in said casing and an extension provided with a socket end portion, an eraser wheel having a shaft extension at one side thereof having detachable engagement with said socket end portion and a shaft extension at the opposite side thereof having an operating handle connection, and means in said casing for rotating said shaft and eraser wheel.

100

4. An erasing attachment for typewriting machines, comprising a clamp adapted for connection with the typewriter frame, an upright arm carried by said clamp and having a casing at its upper end, a rotary shaft having journal bearings in said casing and an extension carrying an eraser wheel, and means located in said casing for rotating said shaft and eraser wheel, including a hollow grooved wheel upon said shaft, a wheel at one side thereof having an internal series of ratchet teeth, a pivoted pawl device upon the side of said grooved wheel having engagement with said ratchet teeth, a flexible strap having attachment at one end to and wound upon said grooved wheel, and spring means within said grooved wheel for rewinding the strap after operation thereof.

110

5. An attachment for typewriting ma-

- chines, having in combination with a rotary shaft having a flexible extension carrying an eraser wheel, means for rotating said shaft and eraser wheel including a grooved 5 wheel and a flexible strap having attachment at one end to and wound upon said grooved wheel, and means for automatically rewinding the strap after operation thereof, push rod mechanism including a clamp device, a push rod having a spring snap-hook seat at one end for the end of said rotary shaft adjacent to the eraser wheel, and a retracting spring. 20
10. end of the flexible shaft adjacent to the eraser wheel, and provided with a retracting spring.
6. An attachment for typewriting machines, having in combination with a rotary shaft having an extension carrying an eraser 15 wheel, means for rotating said shaft and
- eraser wheel including a grooved wheel and a flexible strap having attachment at one end to and wound upon said grooved wheel, and means for automatically rewinding the 20 strap after operation thereof, push rod mechanism including a clamp device, a push rod having a spring snap-hook seat at one end for the end of said rotary shaft adjacent to the eraser wheel, and a retracting spring. 25
In testimony whereof I affix my signature in presence of two witnesses.
